UNITED STATES PATENT OFFICE

109,695

DESIGN FOR A BOTTLE CAP REMOVER

Ernesto Calencia, San Diego, Calif., assignor of one-half to Culmer C. Benton, San Diego, Calif.

Application December 18, 1937, Serial No. 73,695

Term of patent 14 years

To all whom it may concern:

Be it known that I, Ernesto Calencia, a citizen of the United States of America, residing at San Diego, in the county of San Diego and State of California, have invented a new, original, and ornamental Design for a Bottle Cap Remover, of which the following is a specification, reference being had to the accompanying drawing forming a part thereof.

remover showing my new design and Figure 2
is an edge view thereof.

I claim:

The ornamental design for a bottle cap remover
substantially as shown.

ERNESTO CALENCIA.
